IRRADIATOR HOUSING

Felix R. Graf, Lake Hiawatha, and Thomas A. Vizzini,
Morris Plains, N.J., assignors to Radiation Machinery
Corporation, a corporation of New Jersey

Filed Apr. 9, 1969, Ser. No. 16,636

Term of patent 14 years

Int. Cl. D24—02

U.S. Cl. D83—1

Fig. 1

Fig. 2

Fig. 3

Fig. 4

FIG. 1 is a right front perspective view of an irradiator housing showing our new design;

FIG. 2 is a left side elevational view thereof, the right side thereof being a mirror image of FIG. 2;

FIG. 3 is a rear elevational view thereof; and
FIG. 4 is a top plan view thereof.

We claim:

The ornamental design for an irradiator housing, as shown and described.
